UNITED STATES PATENT OFFICE.

JOHN A. MCKEE, OF PHILADELPHIA, PENNSYLVANIA.

CYLINDER FOR WASHING-MACHINES.

967,818.

Specification of Letters Patent. Patented Aug. 16, 1910.

Application filed March 6, 1908. Serial No. 419,458.

To all whom it may concern:

Be it known that I, JOHN A. MCKEE, a citizen of the United States, residing at Philadelphia, county of Philadelphia, and 5 State of Pennsylvania, have invented a certain new and useful Improvement in Cylinders for Washing-Machines, of which the following is a specification.

My invention relates to a new and useful improvement in cylinders for washing machines, and has for its object to provide an exceedingly simple and effective construction by the use of which a flow of water will be caused to pass through the cylinder in one 10 direction when said cylinder is revolved, and in the opposite direction when the cylinder is revolved in an opposite direction, and a further object of my invention is to so arrange the openings in the cylinder as to 15 cause the water to flow from the tank or outer casing through the cylinder below the water level.

With these ends in view, this invention consists in the details of construction and 20 combination of elements hereinafter set forth and then specifically designated by the claims.

In order that those skilled in the art to which this invention appertains may understand 25 how to make and use the same, I will describe its construction in detail, referring by letter to the accompanying drawing forming a part of this specification in which—

Figure 1 is an elevation of a cylinder 30 made in accordance with my improvement. Fig. 2, is a longitudinal section. Fig. 3, an end view thereof. Fig. 4, a cross section at the line $x-x$ of Fig. 1. Fig. 5, a detail of a portion of one of the outer ribs. Fig. 6, an 35 end view of one of the outer ribs. Fig. 7, a detail of a portion of one of the screens. Fig. 8, a detail view of a portion of one of the inner ribs. Fig. 9, an end view of one 40 of the inner ribs, and Fig. 10, an end view of one of the fillers. Fig. 11 a side view of the fillers.

In carrying out my invention as here embodied, A represents the two heads of the cylinder here shown as composed of three 45 sections secured together in any suitable manner, and B are the outer ribs, the ends of which are secured to the heads, and the sides of each of these ribs are inclined inward as clearly shown in Figs. 3 and 4, and C represents the inner ribs, the sides of which are 50

inclined in an opposite direction and at the same angle and are also secured to the heads in such manner as to form two passages D for each inner rib, said passages being at an angle to each other. 60

The outer ribs have the grooves F formed lengthwise thereof, while the inner ribs have corresponding grooves G also formed lengthwise thereof, and when these ribs are in place the grooves lie in the same plane and 65 are adapted to receive the edges of the screens H. These screens H may be made in any suitable manner, but are here shown as being strips of perforated metal and when set in the grooves serve to strengthen 70 the cylinder and permit the free flow of water to and from the same, while retaining the articles to be washed within the cylinder.

E are the fillers adapted to fill the space 75 between the outer and inner ribs where they rest upon the heads so as to make a circular bearing surface for the metal bands I, which latter are secured by screws or otherwise over the ribs and fillers, holding them in place. Where a single compartment cylinder is used there would only be two heads, but as it is customary to use a two compartment cylinder a third head A' serving as a partition is secured midway between the end heads, in which case a third band I' is secured around the ribs. 80

M represents the doors, which are secured to the cylinder by the strap hinges N, and these doors may be locked in their closed 85 position by the bolts O. 90

P and P' represent tumbling ribs secured to the heads and extending lengthwise inside of the cylinder for striking and tumbling the articles that are to be washed when the cylinder is revolved. 95

In the use of power washing machines having outer tanks and inner cylinders, it is customary to revolve the cylinder first in one direction a certain number of revolutions and then in the opposite direction, and when my improved cylinder is used and this method is followed, the water in the outer tank will be caused to flow through one set of the passages D when the cylinder is revolved in one direction and in the opposite set of passages when the cylinder is revolved in the opposite direction, and the angles of these passages are such as to create currents of considerable force below the water level, and this is of considerable importance. 100 105 110

Having thus fully described my invention, what I claim as new and useful, is—

A cylinder for washing machines comprising drum-heads, a main set of ribs having internal surfaces of pyramidal form, interfitting minor rib members having their outer surfaces of pyramidal form, and screens supporting said minor rib members in unsagging relation to said main set of ribs,

the extreme outer surfaces of said minor ribs 10 being within the surfaces of said major ribs.

In testimony whereof, I have hereunto affixed my signature in the presence of two subscribing witnesses.

JOHN A. MCKEE.
